ABSTRACT OF THE DISCLOSURE

Composite antenna comprising in a single structure two units for transmitting two very different wavelengths, $\lambda_1 \gg \lambda_2$, with a beam antenna about $\lambda_1/4$ in length for transmitting the wave of greater wavelength λ_1 , having an end fixed to an antenna set-up dimensioned for transmitting the wave of similar wavelength λ_2 .

The present invention relates to a device comprising fixed combined antennas for radiating energy in diverse wavebands.

The device according to the invention comprises a combination of two antennas interconnected in a fixed manner so that each will transmit in one of two very different ranges of wavelength.

The application of an antenna combination of this nature answers a variety of practical problems, by way of example, the case of a shipwrecked survivor floating at sea on a lifesaving craft which is equipped with transmitters operating on two frequencies, one F_1 being of the order of 8 megacycles (wavelength λ_1 of approximately 38 meters) intended to permit detection up to a distance of the order of 1,250 miles approximately, and the other F_2 being of the order of 240 megacycles (wavelength λ_2 of approximately 1.25 meters) for radio location up to a distance of the order of approximately 95 miles. The two transmitters may be arranged to operate at the same time or in alternate sequence.

In order to minimize the bulk, weight and complexity of such a set, as well as the effort required for its assembly by a physically weakened survivor, it is of importance that the antennas should form a mechanically rigid unit, which should be simple to place in operation. The power applied by means of a battery or of a hand-driven generator being very low, it is necessary moreover that the output of effectively transmitted power should be as high as possible, meaning that the two antennas should have optimum transmission qualities.

According to the invention, a device consisting of fixed combined antennas organized to operate on two very different wavelengths λ_1 and λ_2 , with the former considerably greater than the latter, comprises at least one antenna section which has a length of the order of a quarter of λ_1 for transmission of the longer wavelength λ_1 , connected through the other extremity from the unattached extremity to a device dimensioned for transmission of the shorter wavelength λ_2 .

According to another feature of the invention, in the case of a vertically polarized, relatively long wavelength and of a horizontally polarized, relatively short wavelength, the base of the aforesaid section carries a symmetrical-asymmetrical passage device of the balancing unit type, which feeds two antenna sections each of which has a length of approximately a quarter of the shorter wavelength λ_2 .

According to another feature of the invention, the power at the high frequency F_2 is applied to a co-axial input terminal of the aforesaid balancing unit through a first

2

transformer winding, and the power at the lower frequency F_1 is applied through a winding of a second transformer connected between a ground potential zone and a point of the circuit of the said first transformer winding.

According to another feature, in the case of identical polarization, at least one antenna section is incorporated of an overall length equal to approximately one quarter of λ_1 , whose base is connected to a hollow co-axial conductor short-circuited at the base and of a length close to a quarter of λ_2 , the length of the said antenna section projecting out of the hollow conductor preferably being equal to an odd number of quarter-waves of the shorter wavelength λ_2 .

The invention will now be described in detail with reference to the accompanying drawings, which illustrate several embodiments of the invention, but in no restrictive sense.

FIG. 1 is a diagrammatic illustration of one embodiment of the invention providing for radiation of waves of different polarization, being vertical for the frequency F_1 and horizontal for the frequency F_2 .

FIG. 2 illustrates another embodiment providing for vertical polarization for both waves.

FIG. 3 illustrates another embodiment providing for horizontal polarization for both waves.

FIG. 4 illustrates an embodiment of the invention wherein the ratio between the two wavelengths is 2:1.

In FIG. 1, a VHF transmitter 11 feeds power at the frequency F_2 through a transformer 12, and an HF transmitter 13 feeds power at the frequency F_1 through a transformer 14 to the antenna arrangement in accordance with the present invention.

This antenna arrangement comprises a short length of co-axial lead 23, whose length C is not of a critical nature, 35 which co-axial lead projects into an asymmetrical-symmetrical passage device 16 of the known balancing unit type, shown in section. The passage device 16 comprises a cylindrical metal casing 20 axially containing a length of co-axial lead 21, made up of an inner wire 21i and of an outer conductor 21e, with a base member 22 welded to the extremity of the inner wire 21i. A section of antenna 17, of the whip type, which has the length A , is welded or otherwise secured to the outer side of the short terminal side of the casing 20.

45 A ground potential zone is shown at 15. In the particular case of seaborne craft, this zone may consist of a metal plate conductively linked with the sea.

Within the casing 20, an antenna section 18 extending horizontally and having a length of one-quarter of λ_2 , is 50 connected to the extremity of the outer conductor 21e of the lead 21, whereas another antenna section 18' positioned co-extensively with the antenna section 18, is connected to the inner wire 21i of the lead 21. The total internal length B of the casing 20 is of the order of one-half of λ_2 the segment of co-axial lead 21 and the base member 22 each having a length close to one-quarter of λ_2 . The HF antenna is formed by the external surface of the lead 23, the outer surface of the casing 20, and the outer surface of the antenna section 17. The overall length 60 $C+B+A$ of the HF antenna is of the order of one-quarter of λ_1 .

The current at the frequency F_2 drawn from the secondary winding 12s of the transformer 12 encounters a 65 substantially zero impedance at the input terminal 23i of the co-axial lead 23 and returns on the outer surface of the outer conductor 23e. No current at the frequency F_1 can penetrate inside the casing 20. Thus, the VHF quarter-wave sections 18 and 18' being energized by currents flowing inside the casing 20, decoupling between the two frequencies is almost total; and, there is no unfavorable reaction of any kind of one antenna against the other,

since each is dimensioned independently for its own emission at the most favorable value.

Below the ground potential zone 15, the co-axial lead 23, consisting of the inner conductor 23i and the outer conductor 23e, has its extremity 23i energized at the frequency F_2 by the secondary winding 12s of the transformer 12. The transformer 14 energizes the whip antenna 17 at the frequency F_1 through its secondary winding 14s, connected of the ground potential zone on the one hand, and to the outer conductor 23e of the co-axial lead 23 on the other hand. It is apparent therefore that the two transmitters may operate simultaneously under optimum conditions of radiation.

FIG. 2 applies to an embodiment of the invention providing polarization. The reference numerals 11 to 15 represent similarly designated elements in the system illustrated in FIG. 1. A hollow conductor 31, whose length B is close to one-quarter of λ_2 , is positioned vertically above the ground potential zone 15 and is insulated from the same at its lower closed extremity 31b, the upper extremity being open. A cylindrical conductor 32 connected to the lower extremity 31b is positioned along the axis of the hollow conductor 31. Its upper extremity 32s extends into a vertical section 33 forming a whip antenna having the length A. The length $A+B$ is close to a quarter of λ_1 .

Energization is applied to the base 31b of the conductor 31 through a wire 34 which, by means of a reversing switch 35, may be connected either to a terminal of the secondary winding 12s of transformer 12 or to a terminal of the secondary winding 14s of transformer 14. These two secondary windings have their other terminals connected to ground.

At the frequency F_2 , the impedance of the co-axial cavity formed by the conductors 31 and 32 is infinite or at least very high, since this cavity represents a shorted quarter-wave at this frequency. The current having the frequency F_2 which could reach the section 33 encounters an infinite impedance at the entry to the cavity; therefore, a current of this kind cannot be engendered in the cavity.

To complete the decoupling effect between the two parts of the antenna, it is advantageous for the section 33 to have a length A equalling an odd number of quarter-waves at the frequency F_2 , i.e., the length

$$A = \lambda_2(2k+1)/4$$

k being an integer. Theoretically, the impedance of the section 33 is then zero, or is very low in point of fact, at the frequency F_2 . The coupling between the antennas is reduced still further by this minimum impedance in series with the maximum impedance of the cavity 31.

This decoupling effect is desirable because, if the section 33 were energized by currents at the frequency F_2 , it would radiate in harmonic mode, that is to say that its radiation would run the risk of being aimed at the zenith, or else of having several lobes separated by dead areas in the vertical plane. The presence of such dead areas of radiation would be particularly unfavorable.

The currents having the frequency F_1 flow outside the hollow conductor 31 and along the section 33. The presence of the co-axial cavity having the length B which is small compared to the wavelength at the base of the high frequency antenna is equivalent to the addition of a small inductance in series, which is favorable as a rule, improving radiation at the frequency F_1 .

FIG. 3 corresponds to an embodiment of the invention providing horizontal/horizontal polarization. The reference numerals represent similarly designated elements in the system illustrated in FIG. 2. According to known methods, vertical polarization is transformed into horizontal polarization by duplication of the antenna of FIG. 2, the parts G and D being identical to each other and identical to the antenna of FIG. 2.

The wire 34 is connected to the inner conductor 36i of a co-axial lead acting as a shared "feeder" for the two transmitters 11 and 13. The secondary windings 12s and

14s are connected to the outer conductor of this lead, which is marked 36e. The bases of the parts G and D of the antenna are connected to the secondary winding 37s of a matched transformer 37, whose primary winding 37p is connected to the extremity of the said co-axial lead.

The invention results in a particularly simple form of construction in the case in which the ratio between the frequencies is equal or approximately equal to 2:1, with F_2 approximately equal to $2F_1$ and λ_1 approximately equal to $2\lambda_2$, these two waves being polarized vertically.

In FIG. 4, which illustrates a diagrammatical section of a combined antenna device in accordance with the invention, the latter comprises below a ground potential zone 40, a co-axial feed line comprising an outer conductor 41 and a massive inner conductor 42. The upper portion of the inner conductor 42 is hollowed out into a cylindrical cavity 43 whose upper portion 44 projects beyond the ground potential zone 40 by a length AD equal to a quarter of the wavelength λ_2 , and this cavity 43 has a total depth AG slightly greater than a quarter of the wavelength λ_1 , for example, exceeding a quarter of λ_1 by a length equal to a small fraction of the shorter wavelength of the two, for example, smaller than 10% of the said shorter wavelength. The said cavity 43 contains a central conductor 45 which projects beyond the upper rim of the cavity by a length AC equal to a quarter of λ_2 and which is inserted into the cavity to a depth equal to one quarter of λ_1 . This central conductor is held within the cavity 43 by any appropriate means, for example, by an insulating ring 47.

The lower extremity of the co-axial feed line 41/42 may be connected advantageously to two generators 51 and 52, the one supplying the frequency F_1 and the other 35 the frequency F_2 through a duplexer 50, known per se, of particularly simple type wherein the ratio between the frequencies F_1 and F_2 supplied thereby is 2:1. The device operates in the following manner: For operation at the frequency F_1 , the impedance between the elements 44 and 45 is zero in the plane 46 passing through the extremity A of the cavity, since the cavity 43 represents a quarter-wave open at B. Everything evolves as though a radiating element having a length of one quarter of λ_1 were present above the ground potential zone 40.

45 For operation at the frequency F_2 , the impedance between the elements 44 and 45 is infinite in the plane 46, since the cavity 43 represents a half-wave open at B. Therefore, the currents in the element 44 do not flow into the element 45. This last element 45 moreover has 50 a low impedance in the plane 46, which reduces the coupling between elements 44 and 45 still further. The element 44 then acts as a quarter-wave unit of length $1/4\lambda_2$ radiating above the ground potential zone 40.

The invention is equally applicable in the case in which 55 the wavelengths λ_1 and λ_2 have a ratio between them which is approximately equal to 2:1 instead of being precisely equal to 2:1.

I have shown and described several embodiments in accordance with the present invention. It is understood 60 that the same is not limited thereto but is susceptible of numerous changes and modifications as known to a person skilled in the art and I, therefore, do not wish to be limited to the details shown and described herein, but intend to cover all such changes and modifications as are encompassed by the scope of the appended claims.

I claim:

1. An antenna combination capable of operation on two very different wavelengths λ_1 and λ_2 , the former being longer than the latter, comprising at least one antenna section of the whip-type having a length of substantially one-quarter of the wavelength λ_1 for radiation of energy at the longer wavelength λ_1 , the end of said whip-type antenna section opposite to the free end thereof being formed by an antenna device dimensioned to radiate 70 energy at the short wavelength λ_2 , in which a base mem-

ber of the said whip-type antenna section forming part of said antenna device is connected to a balun having two symmetrical outlet points of which each is connected to one of two further antenna sections of a length equal to substantially one-quarter of the shorter wavelength λ_2 .

2. The combination defined in claim 1, in which electrical energy is supplied by a first transformer whose primary winding is connected to a high-frequency transmitter and whose secondary winding is connected to the conductors of a co-axial input lead on the said balun, and by a second transformer whose primary winding is connected to a second lower frequency transmitter, and whose secondary winding is connected between a ground potential zone and a terminal of the secondary winding of the said first transformer, the two transmitters being arranged to operate at the same time.

3. The combination defined in claim 2 wherein said two further antenna sections are coextensive with a line transverse to said whip-type antenna and extend outwardly from the balun.

4. The combination defined in claim 2 wherein said balun comprises a hollow metal casing of a length $\lambda_2/2$ and having said co-axial input lead projecting axially therein to a length $\lambda_2/4$.

5. The combination defined in claim 4 wherein said two further antenna sections are connected to the respective conductors at the end of said co-axial input lead within said metal casing, said base member being connected between one conductor of said co-axial lead within said casing and the end wall of said casing opposite said co-axial lead.

6. An antenna combination capable of operation on two very different wavelengths λ_1 and λ_2 , the former being longer than the latter, comprising at least one antenna section of the whip-type having a length of substantially one-quarter of the wavelength λ_1 for radiation of energy at the longer wavelength λ_1 , the end of said whip-type antenna section opposite to the free end thereof being formed by an antenna device dimensioned to radiate energy at the short wavelength λ_2 , wherein said whip-type antenna section having an overall length equal substantially one-quarter of the longer wavelength λ_1 includes a base member connected to a hollow conductor short-circuited at the base end thereof, the length of the hollow conductor being close to one-quarter of the shorter wavelength λ_2 .

7. The combination as defined in claim 6, in which the length of portion of said antenna section projecting out of the said hollow conductor is substantially equal to an odd number of quarters of the shorter wavelength λ_2 .

8. The combination defined in claim 7 further including a second antenna section of the whip-type including a base member connected to a second hollow conductor short-circuited at the base end thereof, said one and said second whip-type antennas being coextensive with one another.

9. The combination defined in claim 8 including means for applying energy at the wavelength λ_1 alternately with energy at the wavelength λ_2 to the short circuited base ends of said hollow conductors.

10. An antenna combination capable of operation on two very different wavelengths λ_1 and λ_2 , the former being longer than the latter, comprising at least one antenna section of the whip-type having a length of substantially one-quarter of the wavelength λ_1 for radiation of energy at the longer wavelength λ_1 , the end of said whip-type antenna section opposite to the free end thereof being formed by an antenna device dimensioned to radiate energy at the short wavelength λ_2 , wherein the ratio between the two wavelengths λ_1 and λ_2 is close to 2:1, and further including a coaxial feed line whose outer conductor terminates flush with a ground potential zone and whose inner conductor projects beyond the said ground potential zone by a length equal to substantially a quarter of the shorter wavelength λ_2 to form said antenna device and is hollowed out to a depth slightly exceeding a quarter of the longer wavelength λ_1 from its upper extremity forming a cylindrical cavity which contains a central conductor of an overall length of substantially one-quarter of the shorter wavelength λ_2 plus substantially one-quarter of the longer wavelength λ_1 , said central conductor projecting beyond the upper rim of the said cylindrical cavity by substantially a quarter of the shorter wavelength λ_2 and being inserted into the said cavity to a depth of substantially one-quarter of the longer wavelength λ_1 .

11. The combination defined in claim 10 wherein said central conductor is supported in said cylindrical cavity in spaced relation to said inner conductor.

12. The combination defined in claim 10 including means for energizing said coaxial feed line with energy at the wavelengths λ_1 and λ_2 at the ratio 2:1 in the form of a duplexer.
